UNITED STATES PATENT OFFICE.

EDWARD K. WARREN, OF THREE OAKS, MICHIGAN.

DESIGN FOR A FOUNDATION FOR COLLARS.

SPECIFICATION forming part of Design No. 33,352, dated October 9, 1900.

Application filed June 26, 1900. Serial No. 21,690. Term of patent 14 years.

To all whom it may concern:

Be it known that I, EDWARD K. WARREN, a citizen of the United States, residing at the village of Three Oaks, in the county of Berrien and State of Michigan, have invented and produced an original Design for a Foundation for Collars, of which the following is a specification.

This invention relates to a new and original design for a foundation for collars, of which the following is a specification, reference being had to the drawings forming a part thereof.

Figure 1 is a plan view of a foundation for collars, showing my new design. Fig. 2 is a detail perspective view of the same when it is extended or in the flat.

As shown in the drawings, the leading or material feature of my design consists of the

top and bottom bands A A' and the cross- 20 ribs B. The band A has a slight downward curve both at the rear and front portions of the collar. The band A' is slightly larger than the band A, which gives the form a slight 25 conical shape. The whole is covered with a gauzy or net-like material.

Having thus described my invention, what I claim as new, and desire to secure by Letters Patent, is—

The design for a foundation for collars, as 30 herein shown and described.

In witness whereof I have hereunto set my hand and seal in the presence of two witnesses.

EDWARD K. WARREN. [L. S.]

Witnesses:

WM. C. HALL,
CHAS. K. WARREN.
